(57) **CLAIM**

The ornamental design for a display screen or portion thereof with animated graphical user interface, as shown and described.

DESCRIPTION

FIG. 1 is the first image in a sequence for a display screen or portion thereof with animated graphical user interface showing my new design;

FIG. 2 is the second image thereof;

FIG. 3 is the third image thereof; and,

FIG. 4 is the fourth image thereof.

The appearance of the transitional image sequentially transitions between the images shown in FIGS. 1-4. The process or period in which one image transitions to another forms no part of the claimed design.

The short dashed broken lines in FIGS. 1-4 represent portions of the display screen or portion thereof with animated graphical user interface that form no part of the claimed design.

The dash dot broken lines in FIGS. 1-4 form a boundary of the claimed design and form no part of the claimed design.
